UNITED STATES PATENT OFFICE.

CHARLES A. ANDERSON, OF CHICAGO, ILLINOIS.

'GAS-PUMP.

1,075,183.

Specification of Letters Patent.

Patented Oct. 7, 1913.

Application filed June 9, 1909. Serial No. 501,028.

To all whom it may concern:

Be it known that I, CHARLES A. ANDERSON, a citizen of the United States, residing in the city of Chicago, county of Cook, and 5 State of Illinois, have invented certain new and useful Improvements in Gas-Pumps, of which the following is a specification.

This invention relates to improvements in gas pumps and refers more particularly to 10 a mechanically driven gas pump adapted to be used with a closed circulating system.

Among the salient objects of the present invention are to provide a pump of the above character which operates to automatically 15 draw in and compress charges of gas in each of two similarly constructed chambers, and to continuously circulate the compressed gas through the system; to provide a construction in which the pressure of the gas upon 20 the opposite sides of the piston is so balanced as to reduce to a minimum the working stress upon the actuating parts of the pump and thus materially increase the life and efficiency of the latter; to provide a construction in which certain of the actuating 25 parts are seated in a closed gas containing chamber which is sealed against the escape of gas in a novel manner; to provide an improved construction of the piston rods which 30 permits the use of a unitary structure, and thus obviating the necessity of joints in the rod; to provide novel operative connections between the main driving shaft and the walking beam to which the piston rods are connected; to provide an apparatus which is 35 especially suitable for embodiment in small sizes, so that it may be used for small refrigerating plants; and in general to provide a simple, efficient and improved construction of the character referred to.

The invention consists in the matters hereinafter described and more particularly pointed out in the appended claims.

In the drawings Figure 1 is a vertical sectional view of my improved device; Fig. 2 is a similar sectional view taken on lines 2—2 of Fig. 1. Fig. 3 is a top plan view of the device and showing more particularly the connections between the pump and the external system.

Referring to the drawings 1 designates as a whole the base casting which is provided centrally with a cylindric journal box or walking beam chamber 2 in which is mounted 50 the walking beam 3 in the manner now to be described. One side of the walking beam

chamber is apertured to receive a journal block 4 which is screw threaded into the side wall of the base casting as shown at 5; and in this journal block is rotatably seated one 60 end of a rock shaft 6. The other end of this rock shaft is journaled in a socket member 7 secured to the inner face of the opposite side wall of the chamber 2. Preferably this socket member is cast with the side wall of 65 the base member 1. Upon the central portion of the rock shaft is keyed the walking beam 3 by means of a key pin 8. The inner face of the journal block 4 is provided with an annular boss 9, and between this boss and 70 the adjacent edge of the walking beam is seated an annular washer 10. This washer serves to prevent the escape of gas from the walking beam chamber 2 and accordingly means are provided for holding the washer 75 in constant frictional engagement with the boss 9. To this end the annular socket member 7 is counter-bored at its inner face to receive the set screw 11 which extends through a stuffing box chamber 12 fixed to 80 the outer face of the end wall of the base casting. This stuffing box is provided with the usual packing 13 which is confined in position by means of a packing ring 14. Screw threaded into the stuffing box chamber 85 12 and apertured to receive the set screw 11. The inner end of the latter is slightly 90 counter sunk into the end of the rock shaft 6 as shown at 15 in order to permit the shaft to more readily rock upon its bearings.

The arrangement just described is such 95 that the rock shaft can be adjusted slightly by means of the set screw 11 in order to more firmly hold the washer 10 against the boss 9.

The upper end of the base casting is vertically bored at either side as shown in Fig. 1. Within the upper end of each of these cylindric bores 16 is screw threaded the lower end of a sealed gas chamber 17, 17' respectively. Preferably each of these chambers 100 is provided with an annular flange 42 which abuts against the upper face of the base casting. Within each of these cylinders 17, 17' is seated a hollow elongated piston 18, 18' respectively. Each of these pistons 105 communicates at its lower end with the walking beam chamber and is connected to the walking beam itself by means of an elongated piston rod 19. One end of each of these rods is screw threaded into the closed upper 110 end of its piston as shown at 20, while the other end of the rod is similarly connected

as shown at 21 to an arm 22 pivotally mounted on the adjacent end of the walking beam. As a feature of the present invention in the upper end of each of these piston rods is interposed a flexible connection 23. This connection permits of the piston rod flexing slightly upon the oscillation of the walking beam, while it is at the same time sufficiently rigid to withstand the thrusts of the piston. It will thus be seen that I obviate the necessity of having end joints in the piston rod as is usual in the present constructions.

It may be here stated that the walking beam is preferably immersed in oil, and in order to reduce the friction between the piston and the inner face of its cylinder, the former is provided at its lower end with annular grooves 24 which carry a portion of the oil into engagement with the inner face of the cylinder upon the upward stroke of the piston in an obvious manner. The oil may be admitted into the chamber through any suitable opening as shown at 25.

Describing now the manner of actuating the rock shaft and connected parts, to that end of the former which extends through the journal box 4 is keyed a crank arm or lever 26 which is forked at its upper end as shown at 27 for a purpose hereinafter described. Within suitable bearing supports 28 mounted upon the upper face of the base casting is rotatably journaled the main driving shaft 29. One end of this shaft is provided with a combined driving pulley and fly wheel 30, while to the other end is sleeved an annular disk 31 carrying at its outer face a pin 32 and roller 33. This roller is adapted to ride within the forked extension of the crank arm 26, and as the drive shaft 29 is rotated the crank arm will be oscillated in an obvious manner. Inasmuch as this crank arm is operatively connected to the pistons in the manner hereinafter described it will be seen that the latter will be alternately reciprocated in opposite directions.

In the present instance the pump is shown as connected to opposite sides of the closed system in such manner that each cylinder will alternately receive gas from the exhaust side of the system and force it into the high pressure side thereof. To this end a common inlet pipe 34 is connected to the upper end of each of the cylinders by means of branch pipes 35, 36 respectively. The high pressure side of the system is similarly connected to the upper end of the respective cylinders by means of a common outlet pipe 37 and branch pipes 38, 39 respectively. Within each of these branch pipes 35 and 36 is interposed an inwardly opening check valve 40 while in each of the opposed branch pipes 38 and 39 is interposed an outwardly opening check valve 40'.

In practice the gas is delivered from the

then high pressure side of the pump at approximately eight hundred pounds pressure and returned to the then intake side of the pump at approximately four hundred pounds pressure. These figures may of course be varied but I have found that in small refrigerating plants about the above pressure is required. It may be here stated that the pressure of the gas as it travels through the system is lowered by means of a reducing valve, not shown, or in any well known manner. While the rocking lever or walking beam operates in a substantially sealed chamber and the feed of the pistons is such that there is practically no leakage of gas from one cylinder to the other; nevertheless it is practically impossible to make a positively closed working joint, and accordingly the pressure in the walking beam chamber will usually be in the vicinity of the mean between the maximum and minimum pressures which obtain in the two gas cylinders. Inasmuch as in the present instance this mean pressure is approximately six hundred pounds it may be assumed that the same pressure exists in the walking beam chamber. In other words the differences between the mean pressure and the maximum and minimum pressures in the two gas cylinders is reduced to approximately two hundred pounds, and accordingly the strain upon the actuating parts of the pump is reduced to a minimum.

Assuming that the piston 18 has started upon its upper stroke and the piston 18' in the opposite direction, the cylinder 17 will be forcing gas into the high pressure side of the system while the opposite cylinder is taking in the gas from the low pressure side in the following manner: Gas at high pressure from the cylinder 17 will pass into the branch pipe 38 and through the check valve 40' into the outlet pipe 37. At this time the pressure in the cylinder 17 will have fallen below the low pressure of the system whereupon the check valve 34 of the branch pipe 36 will open and gas rush into the inlet side of the cylinder 17'. At this time the outwardly opening check valve 40' will be closed for the reason that the pressure on the outer side of this valve will exceed the pressure in the cylinder 17'. In the same manner the inwardly opening check valve 40 of the branch pipe 35 will be closed for the reason that the pressure in the cylinder 17 exceeds the pressure in the intake pipe 34. When the pistons have reached the limit of their respective strokes and started in the opposite direction exactly the reverse conditions take place when the pistons are reciprocated in the opposite direction. Inasmuch as the main shaft is being constantly driven it will be seen that the gas will be constantly circulated through the system.

While I have herein shown a preferred

embodiment of my invention it may be more or less varied in details of construction without in any manner departing from the spirit of the invention.

5 I claim as my invention:

1. In a gas pump, the combination with a gas-tight walking beam chamber, of a pair of elongated gas cylinders mounted above said chamber, a hollow elongated piston in 10 each of said cylinders, each of said pistons being of nearly the same length as the cylinders, sealed at their upper ends and open at their lower ends, a piston rod in each of said pistons and extending into the walking-beam 15 chamber, a rock shaft journaled in said latter chamber, a walking-beam carried thereby and operatively connected to each of said rods, a driving shaft, operative connection between the rock shaft and the driving shaft, 20 means for supplying gas to and venting it from the respective cylinders at points above the upper ends of the pistons and from a source independent of the walking-beam chamber, said parts being so arranged that 25 the pressure above the pistons in each cylinder is alternately raised and lowered above a substantially constant pressure in the walking-beam chamber.

2. In a gas pump, the combination with 30 a gas-tight walking-beam chamber, of a pair of relatively narrow elongated gas cylinders mounted above said chamber, a piston in each of said cylinders, each piston being of nearly the same length as its cylinder, sealed 35 at its upper end and open at its lower end, a walking-beam mounted in said walking-beam chamber, a piston rod for each piston, said rods being of relatively small diameter, connected at one end to the walking-beam 40 and also to the upper closed end of the respective pistons, the upper end of said rod having an integral flexible part to permit flexing of the rod upon the actuation of the walking-beam, means for actuating said 45 walking-beam, and means for admitting gas to the upper end of each cylinder from a source independent of the walking-beam chamber, and means for venting gas from each cylinder.

50 3. In a gas pump, the combination with a gas-tight walking-beam chamber, of a pair of gas cylinders, a piston for each cylinder, a journal block seated in one side of said walking-beam chamber, a socket member 55 formed at the opposite side of said chamber, a rock shaft having one end engaging the socket member, and having its opposite end extending out through the journal block, a walking-beam keyed to said rock shaft within 60 said chamber, a washer mounted on the rock shaft and interposed between the walking-beam and the adjacent face of the journal block, means for maintaining a substantially uniform gas pressure within the walking-beam chamber, means for applying end pres-

sure on said rock shaft tending to automatically force the washer into engagement with the journal block to prevent any leakage of gas through the journal block, and operative connections between the pistons and the ends 70 of said walking-beam.

4. In a gas pump, the combination with a gas-tight walking-beam chamber, of a pair of gas cylinders mounted above said chamber, a piston in each of said cylinders, each of said pistons being sealed at the upper 75 ends and open at their lower ends, a piston rod in each of said pistons, a walking-beam mounted in said walking-beam chamber, operative connections between the piston rods 80 and the walking-beam, means for actuating said walking-beam, means for admitting gas at relatively low pressure to the respective cylinders at their upper ends from a source independent of the walking-beam chamber, and means for venting gas from the upper ends of the cylinders at relatively high pressure; there being at all times a substantially uniform pressure in the walking-beam chamber that is intermediate said 85 low and high pressures.

5. In a gas pump, the combination with a gas-tight sealed chamber, having gas therein at substantially uniform pressure, of a pair of gas cylinders, pistons for each cylinder, an actuating member seated in said sealed chamber, operative connections between said actuating member and each piston, means for supplying gas at relatively low pressure to the upper end of each of 95 said cylinders at points above the pistons, means for venting gas at relatively high pressure from each of said cylinders, the pressure on said sealed chamber being at all times intermediate said high and low pressure.

6. In a gas chamber, the combination with a sealed chamber, having gas therein under pressure, a pair of gas cylinders, a piston for each of said cylinders, an actuating member seated in the sealed chamber, operative connections between each piston and actuating member, means for alternately supplying gas at relatively low pressure to each of said cylinders from a source 110 independent of said sealed chamber, and venting it at high pressure from each of said cylinders, the pressure in said sealed chamber being intermediate said high and low pressures.

7. In a gas pump, the combination with a gas-tight walking-beam chamber, of a pair of relatively narrow elongated gas cylinders, hollow pistons in said cylinders, said pistons being open at their lower ends and closed at their upper ends, and of nearly the same length as the cylinders, a walking-beam in said walking-beam chamber, a rock-shaft for said walking-beam, arms pivotally connected to the ends of the walk- 125 130

ing-beam, relatively small piston-rods connected to said arms and to the closed upper ends of their respective pistons, each of said rods having an integral flexible portion near 5 its upper end to permit flexing of the rods as the walking-beam is actuated, means for actuating said walking-beam, means for admitting gas at relatively low pressure to the upper ends of the respective cylinders from 10 a source independent of the walking-beam

chamber, and means for venting gas at relatively high pressure from said cylinders, the gas pressure in the walking-beam chamber being substantially uniform and intermediate said high and low pressures.

CHARLES A. ANDERSON.
